(57) **CLAIM**

The ornamental design for a electrical/pneumatic connector, as shown and described.

DESCRIPTION

FIG. 1 is a top, front perspective view of an electrical/pneumatic connector showing our new design;

FIG. 2 is a front elevational view thereof;

FIG. 3 is a rear elevational view thereof;

FIG. 4 is a top plan view thereof;

FIG. 5 is a side elevational view thereof; and,

FIG. 6 is a bottom plan view thereof.

The broken line in the drawing views is included to show unclaimed subject matter only and forms no part of the claimed design.
